Attorney.

UNITED STATES PATENT OFFICE.

JAMES KELLY, OF PROVIDENCE, RHODE ISLAND.

VENTILATING AND AIR-COOLING MECHANISM.

SPECIFICATION forming part of Letters Patent No. 787,454, dated April 18, 1905.

Application filed June 14, 1904. Serial No. 212,575.

To all whom it may concern:

Be it known that I, JAMES KELLY, a citizen of the United States, residing at the city of Providence, in the county of Providence and 5 State of Rhode Island, have invented certain new and useful Improvements in Air-Cooling Apparatus, of which the following is a specification.

My invention relates to means of ventilating 10 and cooling the air of apartments and buildings, and is especially adapted for use in cotton-mills and other factories where the air is liable to become very dry or full of dust of fibers in consequence of the operation of machinery or the employment of manufacturing 15 processes, which are detrimental to the health or comfort of the workmen; and said invention consists of the novel construction and combination of the several parts, as hereinabove described, and specifically set forth in the claims.

Figure 1 is a side elevation of my improved air-cooling apparatus. Fig. 2 is a view, partly in elevation and partly in section on line X X 25 of Fig. 1, of the fan, its driving mechanism, the case, and the water-spraying devices. Fig. 3 is a front elevation of the water pipe and sprayer. Fig. 4 is a view of the same as seen on line Y Y of Fig. 3. Fig. 5 is a view in 30 central longitudinal vertical section of the separator constituting a part of my said invention. Fig. 6 is a transverse section as seen on line Z Z of Fig. 5. Fig. 7 is a top plan view of the vapor-distributer. Fig. 8 is a view of 35 the same as seen in diametrical section.

Like numerals indicate like parts.

In the drawings the said apparatus is supported by the hangers 1, 2, 3, 4, and 5 from the beam or ceiling 6, said hangers being fastened in position by the headed bolts 7, 8, 9, 10, and 11. The hangers 1 and 2 support the fan-case 12, which, as shown in Fig. 2, is preferably made in two halves or sections, each having circumferential flanges which are fastened together at intervals by bolts 13.

The case 12 has a centrally-located hub or bearing 14, in which is journaled the shaft 15. The opposite end of the shaft 15 is journaled in the bearing 16 of the hanger 5. On said end 50 of the shaft 15 is a collar 17, held to said shaft

by a set-screw 18. At the forward end of the shaft 15 is mounted a fan 19. A pulley 20 is mounted fast on the shaft 15 and is driven by a belt 21 from a shaft rotated by power.

The fan-case 12 has a funnel or air-inlet 22, and at or near the bottom is also an outlet-pipe 23. Cold water is conveyed under pressure through the pipe 24, which is provided with a valve 25. The water-pipe 24 is connected by an elbow 26 with a vertical pipe 27. 55 The pipe 27 enters the inlet 28 of the spray-pipe 29. This spray-pipe is a ring or circular tube having a number of small discharging holes or orifices 30 on the inner side thereof. As shown in Fig. 2, this ring or spray-pipe 29 60 is placed within the funnel or air-inlet 22 of the fan-case 12, with its discharge-orifices diverted inwardly toward the fan 19.

A cylindrical separator 31 is held by the hangers 9 and 10. These hangers have flanges 65 32 and 33. The separator 31 has tangentially-extending flanges 34 and 35. These flanges 32, 33, 34, and 35 are fastened together by bolts 36 37, as seen in Figs. 1 and 6.

The separator 31 has annular flanges 38 and 70 39 at its ends, as shown in Fig. 5. At each end of the separator 31 is a head 40. Each head 40 has an inner annular lip 41 and a central hub 42, whose bore is screw-threaded. The flanges 38 39 are fastened by bolts 43 to the 75 heads 40, respectively. The annular lips 41 fit in the bore of the separator 31, as seen in Fig. 5.

A pipe 44 fits in the outer end of the pipe 23 and screws into the hub 42 of the separator 80 31.

In the separator 31 is loosely mounted the collar 45, which has a concentric annular flange of less diameter and whose outer edge lies against the inner side of one of the heads 85 40, as seen in Fig. 5. The opposite face of said collar 45 has two concentric grooves, one having a larger diameter than the other.

A deflector 46, having its exterior surface somewhat conical in form, as shown in Fig. 5, 90 is supported concentrically in the separator 31 by braces 47, and its inner annular edge has two concentric grooves of the same diameters, respectively, as those of the grooves of the collar 45. Into the smaller of these an-

nular grooves in both the deflector 46 and the collar 45 is mounted a cylindrically-bent sheet of fine wire-gauze, as indicated at 48 in Figs. 5 and 6. A layer or packing of pieces of sponge 49 is placed on the wire-gauze cylinder 48, and another cylindrically-bent sheet of fine wire-gauze 50 is mounted in the larger of the annular grooves of the collar 45 and deflector 46.

- 10 A pipe 51 is screwed into the hub of the head 40, which is nearest the collar 45, and is connected at its opposite end by the elbow 52 to the pipe 53. The pipe 53 has a valve 54. A circular vapor-distributer 55 is screwed 15 upon the bottom of the pipe 53 and has a number of holes 56, through which the vapor is discharged, as represented in Fig. 1.

The separator 31 has a tube 57, which is screw-threaded inside, and a drip-pipe 58 is 20 inserted in said tube. The drip-pipe 58 has a valve 59.

The operation of my said air-cooling apparatus is as follows: Power applied by the belt 21 rotates the pulley 20 and the shaft 15, on 25 which said pulley is fastened. The shaft 15 rotates the fan 19, which is fastened thereon, in such direction as to create a suction of air through the funnel or air-inlet 22, as indicated by the arrows *a a* in Fig. 2. Cold water under pressure flows through the pipe 24 when the valve 25 is open and thence passes 30 through the elbow 26, pipes 27 and 28, and the circular spray-pipe or ring 29, whence it is discharged in small jets, as indicated by the arrows *b b* in Fig. 2, directly against the vanes of the fan 19. The rapid revolution of this fan breaks these jets of cold water into fine spray, and the centrifugal power of the fan discharges the spray from the ends of the 35 vanes against the inner circumference of the case 12. The mingled air and water in the case 12 is forced by the fan 19 out through the pipes 23 and 44 into the separator 31, as indicated by the arrows *c*, Fig. 1, *d e*, Fig. 5, and striking against the conical point of the deflector 46 is divided and directed into the annular space between the inner cylindrical surface of the separator 31 and the cylinder 50 of wire-gauze, as indicated in Fig. 5 by the arrows *f g*. 40 The moisture-laden air then passes through the wire-gauze cylinder 50 and through the layers or packing of sponge 49 and through the wire-gauze cylinder 48, as indicated by the arrows *h* and *i* in Fig. 5. In passing 45 through the sponge layers 49 any excess of moisture is absorbed by the sponges, the pipe 58 when the valve 59 is open allowing any accumulation of water to drip away from the separator, as indicated by the arrow *j* in Fig. 1. 50 From the wire-gauze cylinder 48 the cooled and moistened air passes, as indicated by the arrows *k l*, out through the collar 45, pipe 51,

elbow 52, and pipe 53 and when the valve 54 is open into and through the distributor 55, whence it is discharged through the openings 56. For the direction of these currents see arrows *m n*, and *o* in Figs. 1 and 5.

Instead of sponges any other material may be used which is sufficiently porous or permeable.

I claim as a novel and useful invention and desire to secure by Letters Patent—

1. In an air-cooling apparatus having a power-driven fan, a case wherein said fan is mounted and said case provided with an air-inlet, a pipe arranged to spray water in front of the inlet of said case and upon the blades of said fan, and an outlet-pipe from the bottom of said case, the combination therewith, of a separator, consisting of a cylinder mounted on proper supports; a collar mounted within said cylinder and provided with two concentric grooves; a conical deflector concentrically mounted on supports within said cylinder and provided with two concentric grooves; two cylindrical-shaped sheets of fine wire-gauze whose ends are mounted in the grooves of said collar and said deflector; a layer of porous material interposed between the wire-gauze; a head secured upon and closing one end of said cylinder and having a central annular flange for connecting thereto the end of said outlet-pipe; a head secured upon and closing the other end of said cylinder and having a central annular flange; and a discharge-pipe having its end secured in the flange of last-mentioned head, substantially as set forth.

2. In an air-cooling apparatus, the combination of a rotary fan; means to rotate said fan; a case wherein said fan is mounted; a water-pipe having a sprayer which is adapted to discharge jets of water against said fan; a pipe from the bottom of said case; a cylindrical separator having closed ends, one end of which the last-mentioned pipe centrally enters; two cylinders concentrically mounted in the separator and made of wire-gauze; a deflector concentrically mounted in the separator and provided with a conical surface arranged to deflect the mingled air and water from last-mentioned pipe over and upon said wire-gauze cylinders; a layer of sponge between said wire-gauze cylinders adapted to extract from the mingled air and water passing therethrough excess of moisture; and a discharge-pipe centrally connected to the opposite closed end of said separator, substantially as set forth.

In testimony whereof I affix my signature in the presence of two witnesses.

JAMES KELLY.
